UNITED STATES PATENT OFFICE.

FREDERICK W. STORCK, OF SOMERVILLE, MASSACHUSETTS, ASSIGNOR, BY MESNE ASSIGNMENTS, TO E. CHARLES DROUET, OF SOMERVILLE, MASSACHUSETTS.

STAMP-AFFIXING MACHINE.

1,193,730.

Specification of Letters Patent.

Patented Aug. 8, 1916.

Application filed May 13, 1912. Serial No. 696,872.

To all whom it may concern:

Be it known that I, FREDERICK W. STORCK, a subject of the Emperor of Germany, residing at Somerville, county of Middlesex, 5 State of Massachusetts, have invented a certain new and useful Improvement in Stamp-Affixing Machines, of which the following is a specification, reference being had therein to the accompanying drawings.

10 The invention relates to a stamp or label affixing machine in which the stamps or labels are put up in the form of a ribbon coiled into a roll.

The invention is especially intended for 15 use in connection with mechanism for affixing the stamps or labels to envelopes, postal cards or wrappers and for that reason the invention is shown as embodied in a machine employing mechanism for thus affixing the stamps and for convenience of description the word stamp will be used in a 20 broad sense to include labels.

The invention will be fully understood from the following description taken in connection with the accompanying drawings, 25 and the novel features will be pointed out and clearly defined in the claims at the close of the specification.

In the drawings,—Figure 1 is a vertical 30 section of a machine embodying the invention, showing the plunger in its uppermost and normal position. Fig. 2 is a section on line 2—2 of Fig. 1. Fig. 3 is a vertical section similar to Fig. 1 but with the plunger 35 in its lowermost position and the parts as they appear just after the stamp is affixed to an envelop. Fig. 4 is a sectional view partly broken away, showing the position the parts will assume when the plunger has 40 partly risen after the stamp is attached to the envelop, but before it has tripped the stamp supporting lever. Fig. 5 is a sectional view partly broken away, showing the detent mechanism for the plunger disengaged to permit its up stroke. Fig. 6 is a 45 vertical section through the water tank. Fig. 7 is a section on line 7—7 of Fig. 6. Fig. 8 is a front elevation of the water tank and combined parts. Fig. 9 is a detail view 50 of one of the moistener wicks and its holder. Fig. 10 is a sectional detail view of the feed blade, tearing off blade, and shield. Fig. 11 is a detail view of the stop blade for the

feed blade. Fig. 12 is a detail view of the feed blade. Fig. 13 is a detail view of the 55 tearing off blade. Fig. 14 is a perspective view of the casing. Fig. 15 is a detail view of the front wall of the case. Fig. 16 is a detail view of the back cover. Fig. 17 is a section on line 17—17 of Fig. 1. 60

Referring now to the drawings,—the stamp strip or ribbon is shown in the form of a roll 1, mounted on a stamp shaft 2 which is journaled in the side walls 3 of the case. For convenience of inserting and removing the stamp roll, the side walls are each formed with an outwardly swelled portion 4 extending from the outer edge of the wall at a downward incline toward the middle of the side wall of the stamp roll chamber and forming a clearance space and guide to admit the stamp roll shaft laterally between the two side walls. At the inner ends of said swelled portions there are shoulders or seats 5 which serve as bearings for the 75 stamp roll shaft. There are thus formed guide ways for the stamp roll shaft so that it will be easily guided to its seat and as the outer ends of these guide ways are at a higher elevation than the inner ends, the 80 stamp roll will readily be retained in its seat.

The two side walls 3, 3 are parallel with each other and are spaced apart barely greater than the width of the stamp strip 85 with just sufficient clearance not to impede its movement.

The case is formed with a base portion 6 which is preferably made integral with the side walls 3. The case forms a mount for 90 the plunger and other operative parts of the machine and the base of the machine is intended to bear on top of the envelop when the stamp is being severed from the strip and being affixed. The base of the case 95 therefore is formed with an opening 7 beneath the plunger, large enough for the stamp after it has been severed and carried down by the plunger to be carried through onto the envelop A resting on the table B. 100 The rear end of the case is provided with a cover of peculiar construction which is hinged at its upper end, preferably detachable, and which is provided with means for locking it to prevent access to the interior of 105 the case.

The construction shown is as follows: A hinge pin 8 extends transversely between the two side walls at the upper end spaced a short distance away from the rear end of 5 the front wall 9. The cover 10, which closes the rear opening of the case, is formed with a flange or hook portion 11 which is adapted to hook over the hinge pin so that the cover can turn on said hinge pin. Said 10 cover extends on each side slightly beyond the side walls 3 and is formed with side flanges 12 which lie over the side walls for a short distance so that when the cover is closed there will be no opening shown at the 15 sides. The cover is formed with slots 13 extending in from the upper end to embrace the side walls between the hinge 8 and the rear ends of the front wall 9. At the rear part of the base 6 there is formed an up- 20 turned lip 14 and on the inner face of the cover, near its lower end, there is attached a lock 66 having a bolt 15 which may be operated by any suitable means to engage with the inner face of the lip 14, so that the 25 cover cannot be turned on its hinge. The front wall 9 of the case is fitted to the front edges of the side walls so as to close the front space and is formed with a hole 16 for the passage of the plunger 17. The plunger 30 17 is vertically reciprocable. It is provided with side arms or wings 18, 18, which project through slotted ways 19, 19, in the side walls 3, 3, of the case, the engagement of the said arms with said slots serving to 35 guide the plunger. To the lower end of the plunger rod is hinged a foot 21. In the method of construction shown, the plunger is formed with a reduced lower portion or neck 20 which engages with a slot in the 40 foot within which the neck portion 20 of the plunger is inserted and is pivotally connected therewith by the pin 22. At the upper end of the neck portion 20 of the plunger there is an inclined shoulder 23 on 45 each side which engages the upper side of the foot to aid in retaining the foot normally in an inclined position. A spring 24 tends also to retain the foot in such inclined position but yields to permit the foot to assume a horizontal position when the plunger continues its descent after the toe of the foot has come into contact with the envelop on the down stroke.

A spring 34 coiled around the plunger rod 55 is compressed when the plunger is pushed down and tends to retract the plunger when the downward pressure is released. Means are provided to prevent the plunger from rising after it commences its descent until 60 the advance stamp is severed from the strip, near the end of the down stroke. The means shown are as follows: Pivoted at 25 to the side of the plunger is a pawl 26, one arm of which is provided with a point 27 which 65 engages with a toothed rack 28 secured to

the inner side of one wall of the case. A spring 29 which is also secured at one end to the plunger, the upper end being free, bears against an arm 30 of the pawl and normally retains the point 27 of the pawl in engagement with the rack bar. When the plunger is pushed down the spring 29 yields sufficiently to allow the point of the pawl to ride over the teeth of the rack but prevents the point from becoming disengaged to 75 allow the rising of the plunger until the pawl is tripped as hereinafter described. The spring 29 is formed with an offset 31 and the lower end of the rack is formed with an inwardly extending portion 32. Said 80 inwardly extending portion 32 engages the point 27 of the pawl when the plunger has descended nearly to the bottom of its stroke and throws the pawl completely out of engagement with the rack by turning the pawl 85 on its pivot and at the same time the arm 30 of the pawl will be turned down on the underside of the offset portion 31 as shown in Fig. 5 thus retaining the pawl out of engagement with the rack until the pawl is 90 again tripped in the manner to be described on the upstroke. When the pawl is held in this position by the offset 31 of the spring 29, the plunger will be free to rise under the action of the spring 34 as soon as the 95 downward pressure of the hand of the operator is released. On the ascent of the plunger near the upper end of its stroke, the pawl will strike the projection 33 on the upper end of the rack bar, thereby turning 100 the pawl on its pivot in the reverse direction from what it was turned by the projection 32 on the down stroke, thereby releasing the arm 30 from detention by the offset 31 of the spring 29 and the point 27 will again 105 be brought into engagement with the rack bar.

A feed blade 35 is secured to one side of the plunger 17 by a pin 36, the said blade 35 being formed with an elongated slot 37 110 through which the said pin 36 passes, thereby allowing a limited movement of the plunger with relation to the blade. As shown in the drawings the upper portion of the plunger is cylindrical, although not necessarily so, but preferably cylindrical for convenience. The lower portion 34^a of the plunger is preferably made square and of larger diameter than the cylindrical portion for convenience of attaching the connected parts thereto. This squared out portion of the plunger is formed with a vertically elongated slot or recess 38 into which there extends a pin 39 projecting from and attached to the feed blade 35. A 115 spring 40 is seated as to its lower end upon said pin 39, the upper end of said spring bearing against the upper end of the recess 38, the tension of said spring being such that when the plunger is pressed down it 120 125 130

will carry the feed blade 35 with it until the feed blade 35 is brought to a positive stop in a manner which will be hereafter described. The lower end of the feed blade 5 35 is provided with points 41 which are adapted to pierce the stamp strip at the bend thereof, and is also preferably provided with a series of shorter points or teeth 42 to aid in tearing off the advance 10 stamp in a manner which will be hereinafter described.

A blade 43 which serves to aid in tearing the stamp is secured to the side of the plunger between the blade 35 and the plunger 15 by the same pin 36, which secures the blade 35 to the plunger. The blade 43, however, is so secured to the plunger that it shall always move when the plunger moves, and for this reason the hole 44, through which 20 the pin 36 passes to secure the said blade to the plunger, is not elongated. The blade 43 is formed with an elongated slot 45, through which the pin 39 projects from the blade 35 into the elongated slot 38 of 25 the plunger to permit movement of the blade 43 with relation to the blade 35, and this slot also forms a guide to prevent lateral swaying of the blade 43. Preferably the blade 43 is a thin spring plate and is 30 normally curved slightly inward toward its lower end, so as to press against the feed blade 35 under slight tension when the parts are assembled. Preferably the feed blade 35 is formed with lateral projections or ears 35 46, which extend through narrow slits 47 in the two opposite side walls 3 of the case, which thereby form guides to insure the feed blade 35 traveling in a straight line.

Secured to the base 6 of the case at a 40 slight elevation above the bottom is a stop plate 48, which extends into the path of the feed blade 35, so as to engage the feed blade and stop the downward movement thereof, and said stop plate is provided 45 with notches to receive the points 41 and 42 of the feed blade, so as not to dull the teeth of the feed blade, and also to aid in tearing the stamp.

The stamp strip is fed from the roll 1 50 down over the moistening mechanism, to be hereinafter described, and over the bending lever 49, which upon the up stroke of the plunger bends the stamp strip, so as to bring the advance stamp under the plunger 55 foot 21. For convenience of threading the stamp strip the said bending lever 49 is mounted on top of the moistener tank 50, and therefore the moistener tank and connected parts will now be described together.

The moistener tank 50 is preferably constructed so as to easily be fitted into the case and readily detached therefrom, and to this end the construction is as follows: The tank is made of a width to form an 60 easily sliding fit between the two side walls 3—3 of the case. The lower part of the

case, near the base, is formed with two laterally projecting grooved portions 51 in the base, so that the tank may easily slide into position in the case and form a tongue and groove connection. A block 53 which 70 forms the base of the stop plate 48 forms an inward stop for the end of the tank, so that the tank may be surely positioned when it is shoved into the case.

The tank is formed with a groove 64 in the bottom thereof to afford a clearance for the lip 14 on the base when the tank is shoved into the case. Inserted into the rear wall of the tank is an elastic buffer 65 which projects slightly outside of the wall 75 of the tank, and is engaged by the lower part of the lock case 66, thereby making a yielding pressure on the tank, so as to force the moistening wicks 58 always against the stamp which is drawn down in front of the 80 moistening wicks.

The tank is formed with a compartment 83 to hold water, and compartments for the pads 54. The pad compartments are separated from the water compartment by a partition 55, which is formed with perforations 56, sufficient to allow the pads 54 to be kept 85 properly moistened. Extending from the sides of the pad compartments at their upper ends there are mouth pieces 57, into 90 which are inserted wicks 58, whose inner ends contact with the pad 54, and whose outer ends are adapted to be engaged by the gummed face of the stamp. In order to enable the wicks to be easily inserted and removed each wick is held in a clip 59, the 95 ends of the wick projecting beyond the ends of the clip, so that the rear end of the wick may have a yielding pressure against the moistening pad, and so that the front end of the wick may also have a yielding pressure against the stamp strip. When the wick becomes excessively gummed, or for any reason it is desired to remove the wick, to be replaced by a new one, it can easily 100 be done by grasping the outer end of the wick with the finger and pulling it out. The clip 59 easily slides in and out of the mouth piece 57.

In the upper part of the tank 50 there is 105 a filler opening which is closed by a cap 60. Said cap has a stem which projects into the tank, and has a small air vent 61 there-through. When the whole device is in its 110 normal upright position the level of the water in the tank should be below the vent 61, which admits air as fast as the water is used up. If for any reason the device is tipped over on its side, the water will cover the vent 61, and prevent the water from 115 leaking through the wicks. The tank is 120 made practically air tight, except so far as it enters through the vent 61.

Rising through the top of the tank is a 125 standard 610 which supports a shaft 62, on which is pivoted the bending lever 49. 130

Mounted on said shaft 62 is a spring 63, which engages also the lever 49, and normally retains the rear arm of the lever 49 in contact with the stop which as shown in 5 the drawings is the top of the tank. The forward end of the lever 49 projects into the path of the foot 21 of the plunger, and is adapted to resist the downward feed of the stamp by the feed blade after the points of 10 the feed blade have engaged the stamp strip until the long points 41 of the feed blade have pierced the stamp. Then the continued downward movement of the feed blade will turn the said lever 49 on its pivot, giving 15 an increased tension to the spring 63. When the plunger rises the spring 63 will restore the lever 49 to its normal position, thereby again bending the stamp strip to bring another stamp under the foot of the plunger. 20 Projecting from the front of the air tank are two parallel flanges 67, which straddle the bending lever 49, the outer edges of 25 these two flanges projecting somewhat less distance forward than the bend 68 in the bending lever where the end of the stamp engages the lever. The purpose of these two flanges 67 is that after the advance stamp has been severed and affixed to an envelop, and the plunger begins to rise, and the 30 pivoted lever 49 begins to bend up the next following stamp which is now the advance end of the downwardly projecting stamp strip, there is a tendency of the said advance stamp to curl back, and the edges of these 35 two flanges 67, by engaging the back face of the stamp, help to counteract this tendency.

There is also a tendency, when the plunger rises, for the downwardly hanging stamp strip to be carried up slightly, which would 40 result in getting the stamp strip out of proper position for the feed blade on its down stroke. In order to counteract this tendency, there is provided a thin flexible spring 69 secured to the standard 61, and 45 having a free end projecting at a downward slant far enough forward for its edge to engage the stamp strip and thereby restrain the stamp strip from being carried up when the plunger rises, but it does not interfere 50 with the downward movement of the stamp strip under the positive action of the feed blade and plunger.

Secured to the inner face of the top curved 55 part of the front wall 9, as for instance by a screw 70, is a spring plate 71 which is bent downward and lies against the rear face of the feed blade 83. The stamp strip comes down against the outer face of this plate 71, and as it is drawn down by the feed blade 60 the gummed face of the stamp is drawn across the ends of the moistening wicks 58. This plate 71 prevents the moistening wicks from coming in contact with the feed blade, 65 thus preventing the feed blade from becoming wet and sticky, as would be the case if

the moistening wicks came directly in contact with the feed blade. This spring plate 71 also forms a stationary contact surface for the spring 69, thereby protecting the end of the spring against abrasion by the 70 face of the feed blade when the feed blade rises. The two mouth pieces 57 for the wicks 58 are spaced apart from each other by the two flanges 67, so that the strip is left unmoistened along a narrow space through the 75 middle and the bending lever 49 engages the stamp on this dry portion, so that the bending lever is prevented from becoming gummed and sticky.

A lever 72 is fulcrumed on a shaft 73 80 mounted in a bracket 74, the free end of said lever 72 projecting beneath the foot of the plunger, so that it will support the under portion of the advance stamp until the toe of the plunger foot 21 engages the stamp 85 while the feed knife and the foot of the plunger are carrying the stamp down to the envelop, and so that the stamp will be delivered to the envelop in a horizontal position. The lever 72 is swung down on its pivot by 90 the action of the plunger foot in advancing. When the plunger rises the bending lever 49 will swing forward again to bend the stamp which then becomes the advance stamp, and it is important that the lever 72 should be 95 prevented from swinging up on its pivot until after said advance stamp has become bent. To this end means are provided for latching the lever 72 in its most turned down position until after the plunger has risen sufficiently for said advance stamp to be bent. The means provided for this are as follows: The short arm of the lever 72 is formed with a ratchet tooth 75. A bent lever 76 is pivoted at 77, and has an arm 78 which projects over 105 the upper side of the plunger foot 21. A spring tends to turn the lever 76 on its pivot in a direction to bring a portion of the lever into engagement with the under face of the tooth 75 to prevent the lever 72 from swinging up on its pivot. When the plunger foot moves downward away from the arm 78 of the lever 76 said lever 76 is free to respond to the said action of the spring, so that when the plunger has reached the end of its down 110 stroke said lever 72 will be latched, and it will remain latched until the plunger has risen far enough on its up stroke for the plunger foot to engage the overhanging arm 78 of the lever 76, thereby turning the said lever 76 to trip it from the ratchet tooth 75. Then the lever 72 will be turned up again by a spring 79. The spring 79 is shown in the drawings as connected with both the lever 72 and the lever 76. It is obvious that 115 a separate spring may be employed for each lever 72 and 76 instead of making one spring actuate both levers.

In order to insert a stamp roll the cover 10 is unlocked then swung back on its hinge and 130

removed, and the moistener tank is withdrawn. The stamp roll shaft, as already described, is slightly longer than the space between the flat inner faces of the side walls 3 so as to fit into its bearings between the bulging cheeks 4 of the side walls, while the stamp roll is only of sufficient width to easily pass between the flat inside faces of the side walls. The stamp roll shaft with the 10 roll of stamps mounted thereon is now dropped into its bearings, and the end of the strip is drawn down and bent along the first line of perforations and hooked onto the 15 long teeth 41 of the feed blade along the line of perforations. The moistener tank is then shoved into place and the cover placed on the case and locked, and the device is now ready for use. When it is desired to affix a 20 stamp to an envelop which is placed on a table the device is placed upon the envelop with the opening 7 in the base over that portion of the envelop to which it is desired to affix the stamp, and the plunger is forced down by a quick pressure of the hand. 25 When the plunger moves down, the feed blade 35 by its engagement with the stamp at its bend, as already described, will carry the stamp strip down. As the feed blade descends it turns the levers 49 and 72 back on 30 their pivots. When the feed blade 35 comes into engagement with the stop plate 48 the short teeth 42 of the feed blade will also be forced through the stamp strip and by this time the toe of the hinged foot 21 will come 35 into engagement with the free end of the stamp and clamp it to the envelop beneath the plunger. As the plunger descends farther the heel of the foot will be brought down into a horizontal position. While the 40 foot is being thus turned into a horizontal position after its toe has clamped the stamp to the envelop the tearing blade 43 which continues its descent with the plunger cooperates with the heel of the foot in tearing 45 the advance stamp from the strip along the line which has been engaged by the teeth of the feed blade the stamp strip having been weakened along this line by the teeth of the feed blade so as to insure the tearing of the 50 stamp along that line only.

During the downward feed of the stamp strip the next following stamp behind the advance stamp will be drawn along in engagement with the moistening wicks so as 55 to be already moistened ready for the affixing of the next stamp. When the plunger reaches the bottom of its stroke the supporting lever 72 will be latched down by the tooth 75 engaging with the lever 76, as 60 already described. Then when the pressure upon the plunger is released the spring 34 will carry the plunger up again, and the lever 49 will bend the newly advanced stamp along its first line of perforations, 65 and when the plunger has risen far enough

for the lever 76 to be disengaged from the tooth 75 the supporting lever 72 will be turned up by its spring, so that it will be in position to support the free end of said advance stamp as before.

70

By the form of construction of my device the advance stamp, when in its bent condition ready for the descent of the plunger, as shown in Fig. 1 is in contact with the supporting lever 49 only at one point, 75 namely at the bend of the strip in a dry portion thereof. The only other contact point of the bent advance stamp is where it is engaged by the toe of the supporting lever 72.

80

The device is especially intended for use where a large number of envelops are to be stamped one after the other. If after a period of non use the advance stamp which was moistened when the machine was last 85 used has become dry the envelop itself may be moistened in a proper place to receive the first stamp, and after that the stamps will be moistened automatically, so that it will not be necessary to moisten the envelop. 90

What I claim is:—

1. A vertically reciprocable plunger, a stamp strip container, reciprocable feed mechanism actuated by the plunger for feeding the strip in a vertical path parallel 95 with the line of movement of the plunger, means for moistening a part of said parallel portion of the strip during said vertical movement, means for bending the advance moistened portion of the strip after it has 100 been moistened, and means for severing and affixing the advance portion of the strip to an envelop or the like.

2. In a stamp affixing machine, a stamp strip container, a vertically reciprocable 105 stamp strip feed blade which feeds the stamp strip in a vertical path parallel with the path of movement of the feed blade, means adjacent the path of movement of the said feed blade for moistening each stamp of 110 the strip in succession while it is traveling in a vertical path parallel with the path of movement of the feed blade, means for severing the advance moistened stamp from the strip, and means for affixing the severed stamp to an envelop or the like.

3. In a stamp affixing machine, a stamp strip container, a reciprocating feeding mechanism, means for bending the advance portion of the strip around said feeding mechanism, 120 a stationary moistening device which is engaged by the strip during its feeding movement, thereby moistening a part of the strip, and a severing device for severing the advance portion from the strip.

125

4. In a stamp affixing machine, a stamp strip container, a reciprocable feeding mechanism which feeds the strip, means for bending the advance portion of the strip around the said feeding mechanism, means preventing 130

- the feeding mechanism from retrograde movement until its feeding stroke is completed, and a moistening device which engages the strip during its feeding movement thereby moistening a part of the strip.
5. In a stamp affixing machine, a stamp strip container, a reciprocable plunger, a reciprocable feeding mechanism adjacent to and traveling parallel to and with the plunger, means for preventing said reciprocable feeding mechanism from retrograde movement until the feeding stroke is completed, and means for severing the advance portion of the strip and affixing it to an article positioned to receive it.
10. In a stamp affixing machine, a stamp strip container, a reciprocable plunger, a reciprocable feeding mechanism mounted upon said plunger, means preventing the feeding mechanism from retrograde movement until the feeding stroke is completed, and means for severing the advance portion of the strip and affixing to it an envelop or the like.
15. In a stamp affixing machine, a stamp strip container, a reciprocable plunger, a reciprocable stamp strip feeding mechanism, a lever which bends the stamp strip so that it can be operated upon by the said feeding mechanism, and means for preventing retrograde movement of the unrolled portion of the stamp strip.
20. In a stamp affixing machine, a stamp strip container, a reciprocable stamp strip feeding mechanism and a lever which bends the stamp strip and retains it so that it can be operated upon by the feeding mechanism, said feeding mechanism moving the bent portion of the stamp toward an envelop positioned to receive it, and means for severing a stamp from the bent portion and affixing it to an envelop or the like.
25. In a stamp affixing machine, a stamp strip container, a reciprocable plunger, a stamp bending lever mounted upon said moistening device, and adapted to bend the advance portion of the strip so that it can be operated upon by the feeding mechanism.
30. In a stamp affixing machine, a stamp strip container, a reciprocable plunger, a feeding mechanism, a moistening device, a stamp bending lever mounted upon said moistening device, and adapted to bend the advance portion of the strip so that it can be operated upon by the feeding mechanism.
35. In a stamp affixing machine, a stamp strip container, a reciprocable plunger, a feeding mechanism, a detachably mounted moistening device, and means mounted upon said moistening device for preventing the stamp strip from retrograde movement.
40. In a stamp affixing machine, a stamp strip container, a reciprocable plunger, a stamp strip feeding mechanism, a moistening device, and means mounted on said moistening device for preventing the stamp strip from retrograde movement.
45. In a stamp affixing machine, a stamp strip container, a reciprocable plunger, a stamp strip feeding mechanism, a moistening device, and means mounted on said moistening device comprising a pad,

- means whereby the pad is kept in a wet condition, a wick detachably mounted in such relation to the pad that one end of the wick contacts with the pad while the other end of the wick projects toward the path of movement of the stamp strip into such position that it is engaged by the gummed face of the moving stamp, and means for severing a moistened stamp from the strip and affixing it to an envelop or the like.
50. In a stamp affixing machine, a reciprocable plunger, a feed blade mounted upon said plunger, a support for a stamp strip roll, means for bending the stamp strip over the feeding edge of the feed blade, means cooperating with the feed blade whereby the feeding movement of the plunger moves the stamp strip forward, a moistening device alongside of the path of the stamp strip and which is engaged by one of the stamps in its forward movement thereby moistening the stamp, and means for severing the advance stamp from the strip and affixing it to an envelop or the like.
55. In a stamp affixing machine, a reciprocable plunger, a feed blade mounted upon said plunger and carried thereby, a support for a stamp strip roll, a moistening tank located alongside of the path of the feed blade, a stamp bending lever mounted on said moistening tank, said lever extending beneath the path of movement of the feed blade and plunger, and being adapted to bend the end of the stamp strip around the feeding end of the feed blade, said feed blade being adapted to engage the stamp strip at its bend and to carry the stamp strip forward thereby turning said bending lever back on its pivot, a moistener wick projecting from said moistener tank and adapted to engage the gummed face of the stamp strip as the stamp strip is carried forward by the feed blade, and means for severing the advance stamp from the strip and affixing it to an envelop or the like.
60. In a stamp affixing machine, a reciprocable plunger, a feed blade carried by said plunger and having a spring seat, a support for a stamp strip roll, means for bending the stamp strip around the feeding end of the feed blade, whereby the feed blade carries forward the bent stamp strip, a stop which is engaged by the feed blade after the plunger has partially completed its stroke, said spring seat for the feed blade yielding to allow the plunger to continue its stroke after the feed blade is brought to a stop, and a tearing off blade secured to the plunger alongside of said feed blade, and which engages the stamp and aids in tearing it off when the plunger continues its movement after the feed blade is brought to a standstill, and means for affixing the detached stamp to an article positioned to receive it.
65. In a stamp affixing machine a recip-

reciprocable plunger, a feed blade carried by the plunger and having a spring seat, a support for a stamp strip roll, means for bending the stamp strip around the feeding end of the feed blade, whereby the feed blade carries forward the bent stamp strip, a stop which is engaged by the feed blade after the plunger has partially completed its stroke, said spring seat for the feed blade yielding to allow the plunger to continue its stroke after the feed blade is brought to a stop, a tearing off blade secured to the plunger and which engages the stamp and aids in tearing it off when the plunger continues its descent after the feed blade is brought to a standstill, said tearing off blade being a sheet of thin spring metal which faces said feed blade, the lower end of said tearing off blade being curved toward said feed blade and engaging therewith, and means for affixing the detached stamp to an article positioned to receive it.

17. In a stamp affixing machine, a reciprocable plunger, a feed blade carried by the plunger, a support for a stamp strip roll, a moistening tank located alongside of the path of the feed blade, a pivoted stamp bending lever mounted on said moistener tank, said lever extending beneath the path of movement of the feed blade and plunger and being adapted to bend the end of the stamp strip around the feeding edge of the feed blade, said feed blade being adapted to engage the stamp strip at its bend and to carry the stamp strip forward thereby turning said bending lever back on its pivot, moistener wicks projecting from said moistener tank and adapted to engage the gummed face of the stamp strip while the stamp strip is carried by the feed blade, forming moist lines upon said stamp with a dry space between them, said bending lever being located between said two moistener wicks so that it engages the stamp in the dry space between the two moist lines.

45 18. In a stamp affixing machine, a reciprocable plunger, a support for a stamp roll, means carried by the plunger whereby the strip is fed from the roll and carried forward, moistener wicks extending laterally adjacent to the downward path of the stamp strip in such manner that the feed mechanism trails the stamp strip in contact with the said moisteners, means for bending the strip so that the moistened stamp extends beneath the plunger, and means whereby the moistened stamp is severed from the strip and carried by the plunger into contact with an envelop positioned to receive it.

60 19. In a stamp affixing machine, a reciprocable plunger, a support for a stamp roll, means carried by the plunger whereby the strip is fed from the roll and carried forward, a moistener wick extending laterally adjacent to the forward path of the stamp strip, in such manner that the feed mech-

anism trails the stamp strip in contact with the said moistener, means for bending the stamp strip so that the moistened stamp extends beneath the plunger, means whereby the moistened stamp is severed from the strip and carried by the plunger into contact with an envelop positioned to receive the stamp, a casing which forms a mount for said stamp roll and which incloses the bending mechanism and moistener and feed mechanism, a slide way in which said moistener tank is detachably engaged with the case, a stop for the inner end of the moistener tank, an elastic buffer in the wall of the moistener tank, a cover for one end of the case which when closed engages said buffer so that a yielding pressure is made against the moistener tank, and the moistener wick is held under tension against the stamp strip.

85 20. In a stamp affixing machine, a moistener tank for moistening the stamp strip having a water compartment, a pad compartment separated from the water compartment by a perforated partition, a moistener pad in said second compartment, a laterally extending mouth piece for a moistening wick, a moistener wick and a metallic holder therefor which has a sliding fit in said laterally extending mouth piece whereby the holder and wick may be moved into and out of the mouth piece, means for feeding a stamp strip to cause a stamp to engage the wick and means for severing the moistened stamp from the strip and affixing it to an article positioned to receive the stamp.

21. In a stamp affixing machine, a reciprocable plunger, a feed blade carried by the plunger, a support for a stamp strip roll, a moistening tank located alongside of the path of the feed blade, a pivoted stamp bending lever mounted on said moistener tank, said lever extending beneath the path of movement of the feed blade and plunger, and being adapted to bend the end of the stamp strip under the feeding end of the feed blade, said feed blade being adapted to engage the stamp strip at its bend and to carry the stamp strip forward, thereby turning said bending lever back on its pivot, a moistener wick projecting from said moistener tank and adapted to engage the gummed face of the stamp strip as the stamp strip is fed by the feed blade, means for severing the advance stamp from the strip and affixing it to an envelop positioned to receive it, a thin, flexible spring mounted above said moistener tank having a free end which extends at a downward inclination to engage the side of the stamp strip and which aids in preventing the stamp strip from being lifted by the said plunger on its up stroke, but which yields to allow the downward feed of the stamp strip on the down stroke of the plunger.

22. In a stamp affixing machine, a reciprocable plunger, a feed blade mounted on the plunger, a support for a stamp strip roll, means for bending the stamp strip over the edge of the feed blade, means cooperating with the feed blade whereby the movement of the plunger moves the stamp strip forward, a moistening device having a moistener wick alongside of the path of the stamp strip and which is engaged by one of the stamps as it is fed, thereby moistening the stamp, means for severing the moistened stamp from the strip and affixing it to an envelop positioned to receive it, a spring plate mounted in the case between the feed blade and the stamp strip which extends approximately to the bending line of the stamp strip and which serves as a shield to prevent the moistener wick from coming in contact with the feed blade. 10
23. In a stamp affixing machine, a reciprocable plunger, a feed blade carried by the plunger, a support for a stamp strip roll, means whereby the stamp strip is fed by the feeding stroke of the plunger, means whereby on the feeding stroke of the plunger a stamp is severed from the strip and carried to an envelop positioned to receive it, means for affixing the severed stamp to an article positioned to receive it, and means whereby the plunger is prevented from making its return stroke after it has completed its feeding stroke until the feeding stroke is fully completed. 15
24. In a stamp affixing machine, a reciprocable plunger, a feed blade carried by the plunger and adapted to engage the stamp strip and feed the same, means for stopping the movement of the feed blade before the plunger has completed its stroke, a tearing off blade carried by the plunger and continuing to move therewith after the feed blade has stopped and aiding in tearing the advance stamp from the strip, and means for affixing the severed stamp to an article positioned to receive it. 20
25. In a stamp affixing machine, a reciprocable plunger, a casing to receive a stamp roll, means for bending the end of the stamp strip across the path of the plunger, means carried by the plunger adapted to engage and feed the stamp strip, said casing having two side walls spaced apart a distance substantially equal to the length of the stamp roll, a shaft on which the stamp roll is mounted projecting at each end somewhat beyond the end of the stamp roll, said side walls of the case being formed with recessed guide-ways extending from the outer edge for some distance inwardly in the inner faces of the walls and affording clearance space for the admission of the stamp roll shaft, the inner ends of said guide-ways forming seats which serve as bearings for said stamp roll shaft, and means for severing a stamp from the strip and means for affixing the severed stamp to an article positioned to receive it. 25
26. In a stamp affixing machine, a stamp roll shaft, a casing having two side walls spaced apart from each other and formed with recessed guide-ways extending from the outer edge for some distance inwardly in the inner faces of the walls and affording clearance space for the admission of the stamp roll shaft, the inner ends of said guide-ways forming seats which serve as bearings for the said shaft, said guide-ways and bearings being closed on the outer sides, means to engage and feed the stamp strip, and means for severing a stamp from the strip and for affixing it to an article positioned to receive it. 30
27. In a stamp affixing machine, a stamp roll shaft, a casing having two side walls spaced apart from each other and formed with recessed guide-ways extending from the outer edge for some distance inwardly in the inner faces of the walls and affording clearance space for the admission of the stamp roll shaft, the inner ends of said guide-ways forming seats which serve as bearings for the said shaft, said guide-ways and bearings being closed on the outer sides, means to engage and feed the stamp strip, means for severing a stamp from the strip and for affixing it to an article positioned to receive it, a hinge pin extending transversely between said two side walls at the upper portion thereof, and a separable cover to close the entrance to the guide-ways for the stamp roll shaft, said cover having a hook portion which engages with said hinge pin so that the cover may turn thereon, and which is readily detachable therefrom. 35
28. In a stamp affixing machine, means for feeding a stamp strip, a moistening device located alongside the path of movement of the strip and a detent mounted on the moistener which engages the stamp strip and which prevents the strip from retrograde movement and which yields to allow its feed movement. 40
29. In a stamp affixing machine, stamp strip feeding mechanism having a feeding edge, a pivoted lever adapted to bend the stamp strip across the path of movement of the feeding edge of the feeding mechanism, and moistener wicks adapted to engage the face of the stamp strip while the stamp strip is being moved, thereby forming moist lines upon said stamp with a dry space between them, said bending lever being located so that it engages the stamp in the dry space between the moist lines. 45
30. In a stamp affixing machine, a stamp strip container, a reciprocable stamp strip feeding mechanism, a lever which bends the stamp strip into position to be engaged by the feeding mechanism along the line of the bend, and means for moistening a portion of said stamp strip container, and means for severing a stamp from the strip and means for affixing the severed stamp to an article positioned to receive it. 50

the unrolled strip back of said bent portion during each feeding operation whereby at the next bending operation of the lever the portion of the strip which is to be bent is 5 already moistened.

31. In a stamp affixing machine, a reciprocable plunger, a feed blade mounted upon said plunger, a support for a stamp strip roll, means for bending the stamp strip 10 across the path of the feeding edge of the feed blade, a moistening device alongside of the path of the stamp strip and which is engaged by one of the stamps in its forward movement thereby moistening the stamp, 15 and means for severing the advance stamp from the strip and affixing it to an envelop or the like.
32. In a stamp affixing machine, a reciprocable plunger, a feed blade actuated by 20 said plunger, a support for a stamp strip roll, a stamp bending lever extending across the path of movement of the feed blade and plunger, and being adapted to bend the end of the stamp strip around the feeding edge 25 of the feed blade, said feed blade being adapted to engage the stamp strip at its bend and to carry the stamp strip forward, a moistener wick adapted to engage the face of the stamp strip as the stamp strip is carried forward 30 by the feed blade, and means for severing the advance stamp from the strip and affixing it to an envelop or the like.

33. In a stamp affixing machine, a reciprocable plunger, a feed blade carried by the 35 plunger, a support for a stamp strip roll, a pivoted stamp bending lever adapted to bend the end of the stamp strip across the path of the feeding edge of the feed blade, said feed blade being adapted to engage the 40 stamp strip at its bend and to carry the stamp strip forward thereby turning said bending lever back on its pivot, and moistener wicks adapted to engage the gummed face of the stamp strip while the stamp strip 45 is carried by the feed blade.

34. In a stamp affixing machine, a reciprocable plunger, a support for a stamp roll, means whereby the strip is fed from the roll and carried forward, a tank having a moistener wick which is engaged by the stamp strip, means whereby the moistened stamp is severed from the strip and carried into contact with an envelop positioned to receive the stamp, a casing which forms a 50 mount for said stamp roll and which incloses the moistener and feed mechanism, a slide way in which said moistener tank is detachably engaged with the case, a stop for the inner end of the moistener tank, an elastic buffer in the wall of the moistener tank, and a cover for one end of the case which when closed engages said buffer so that a yielding pressure is made against the moistener tank, and the moistener wick 55 is held under tension against the stamp strip.

35. In a stamp affixing machine, a moistener tank for moistening the stamp strip having a moistener pad therein, a laterally extending mouth piece for a moistening wick, a moistener wick, a metallic holder 70 therefor which has a sliding fit in said laterally extending mouth piece whereby the holder and wick may be moved into and out of the mouth piece, means for feeding a stamp strip to cause a stamp to engage the 75 wick, and means for severing the moistened stamp from the strip and affixing it to an article positioned to receive the stamp.

36. In a stamp affixing machine, a support for a stamp strip roll, a moistener, a reciprocable plunger, feed mechanism actuated by the plunger on the down stroke 80 which feeds the stamp strip and moves the gummed face of the stamp strip in engagement with said moistener, means for severing the moistened advance stamp from the strip and affixing it to an envelop positioned to receive it, a flexible spring which extends 85 at a downward inclination to engage the side of the stamp strip and which aids in 90 preventing the stamp strip from being lifted by the said plunger on its up stroke, but which yields to allow the downward feed of the stamp strip on the down stroke of the plunger.

37. In a stamp affixing machine, a reciprocable feed blade, a support for a stamp strip roll, means for bending the stamp strip over the edge of the feed blade, a moistening device having a moistener wick alongside of the path of the stamp strip and which is engaged by one of the stamps as it is fed, thereby moistening the stamp, means for severing the moistened stamp from the strip and affixing it to an envelop 100 positioned to receive it, and a guard mounted between the feed blade and the stamp strip which serves as a shield to prevent the moistener wick from coming in contact with the feed blade.

38. In a stamp affixing machine, a stamp strip container, a reciprocable stamp strip feeding mechanism, a lever which bends the advance portion of the stamp strip into position to be engaged by the feeding mechanism along the line of the bend, and means for moistening a portion of the unrolled strip back of said bent portion during each feeding operation whereby at the next bending operation of the lever the portion of 110 the strip which is to be bent is already moistened.

39. A reciprocable plunger, a stamp strip container, vertically reciprocable feed mechanism actuated by the plunger for feeding 115 the strip in a vertical path parallel with the line of movement of the plunger and feed mechanism, means for moistening a part of said parallel portion of the strip during said parallel vertical movement, and means 120 125 130

for severing and affixing to an envelop or the like the advance portion of the strip.

40. In a stamp affixing machine, a feed device for a stamp strip having a reciprocable plunger, a feed blade mounted on said plunger, means for positioning the end of the stamp strip in a path adjacent to the path of said feed blade, means for bending the end stamp upward into the path of said plunger and feed blade in a manner whereby said feed blade in its descent may engage the stamp strip at the line of perforations between the end stamp and the following stamp and feed the strip, and means whereby the end stamp may be severed from the strip, said plunger being adapted to press the severed stamp against an envelop or the like.

41. In a stamp affixing machine, a feed device for a stamp strip having a reciprocable plunger, a feed blade mounted on said plunger and extending below the end thereof, means for positioning the stamp strip in a path adjacent to the path of the plunger, means for bending the end stamp upward into the path of said plunger and feed blade in a manner whereby said feed blade in its descent may engage the stamp strip at the line of perforations between the end stamp and the following stamp and feed the strip, a stop plate adapted to coöperate with said feed blade in severing the end stamp from the strip and in limiting the feed movement of the strip and a yielding connection between said feed blade and said plunger whereby said plunger may continue its descent, after said feed blade has engaged said stop plate, and press the severed stamp against an envelop or the like.

40. 42. In a stamp affixing machine, a feed device for a stamp strip having a reciprocable plunger, a foot hinged to the lower end thereof and a spring adapted yieldingly to hold said foot in a normally tilted position, a feed blade mounted on said plunger and normally extending below the elevated end of said foot, means for positioning a stamp strip beneath said plunger and feed blade in a manner whereby said feed blade in its descent may engage the stamp strip at a line of perforations between the end stamp and the following stamp and feed the strip, a stop plate adapted to coöperate with said feed blade in severing the end stamp and in limiting the feed movement of the strip and a yielding connection between said feed blade and said plunger whereby said plunger may continue its descent, after said feed blade has engaged said stop plate, thereby causing the inclined toe of said foot to clamp one end of the end stamp to an envelop or the like while the heel of said foot, as it assumes a horizontal position, assists in tearing said stamp from the strip.

43. In a stamp affixing machine, a feed device for a stamp strip having a reciprocable plunger, a feed blade mounted on said plunger, points on said feed blade, and means whereby a stamp strip may be positioned beneath said plunger and feed blade in a manner whereby a line of perforations may lie in the path of said feed blade, said plunger and feed blade being provided with a spring which normally retracts said plunger and feed blade a short distance above said line of perforations, said points on said feed blade being adapted to strike and pierce said strip at said line of perforations upon the descent of said feed blade and thus engage the strip firmly and feed the same in a path parallel with the movement of the feed blade and the plunger, means for severing the advance stamp from the strip, and means for affixing the severed stamp to an envelop or the like.

44. In a stamp affixing machine, a feed device having a reciprocable feed blade provided with points adapted to pierce a stamp strip and thereby engage and forward it, means whereby the end of said stamp strip may be positioned beneath said feed blade in a manner whereby a line of perforations may lie in the path thereof and a stop plate provided with recesses adapted to register with said points on said feed blade, said stop plate and feed blade being adapted to coöperate in severing said stamp strip and limiting its feed movement and means for affixing the severed stamp to an envelop or the like.

45. In a stamp affixing machine, a feed device for a stamp strip having a plunger, a feeding element mounted on said plunger adapted on the down stroke thereof to engage and forward a stamp strip in a manner whereby upon the elevation of said plunger the end stamp of said strip may project below said plunger and feeding element, a rocking lever and means whereby said rocking lever, upon the elevation of said plunger, may be actuated to bend said end stamp upward into the path of said plunger and feeding element so that the line of perforations between the end stamp and the following stamp is positioned beneath said feeding element and may be engaged thereby on its downward stroke said downward stroke also operating to feed the stamp strip and to turn said lever back on its fulcrum and out of the path of said plunger and feeding element, means actuated by the plunger to sever the advance stamp from the strip, and means for affixing the severed stamp to an envelop or the like.

46. In a stamp affixing machine, a feed device for a stamp strip having a plunger, a feeding element mounted on said plunger, means for bending the end of a stamp strip upward into a position beneath said plunger

and bending element, a member adapted to press the end of the advance stamp against the under side of said plunger during its downward or feeding stroke, said member 5 being movable in a manner whereby it may be forced by said plunger, on its downward stroke, out of the path thereof, means actuated by the plunger to sever the advance stamp from the strip, and means for affixing

10 the severed stamp to an envelop or the like.

47. In a stamp affixing machine, a feed device for a stamp strip having a plunger, a feeding element mounted on said plunger, means for bending the end of a stamp strip 15 upward into a position beneath said plunger and feeding element, a member adapted to retain the end of the advance stamp against the under side of said plunger during its downward or feeding stroke, said member 20 being movable in a manner whereby it may be forced by said plunger, on its downward

stroke, out of the path thereof, a spring normally acting to press said movable member against the under side of said plunger, a latch adapted to restrain the upward movement of said movable member after it has been forced out of the path of said plunger, means coöoperating with said plunger adapted upon the partial retraction thereof, to trip said latch and permit said spring 25 again to elevate said movable member into operative position, means actuated by the plunger to sever the advance stamp from the strip, and means for affixing the severed stamp to an envelop or the like. 30

35 In testimony whereof I affix my signature, in presence of two witnesses.
